UNITED STATES PATENT OFFICE

2,514,628

ELECTRIC CORD HOLDER AND CONNECTOR

Edmundo Cortes, New York, N. Y.

Application June 12, 1946, Serial No. 676,160

2 Claims. (Cl. 242—107)

1

This invention relates to improvements in electrical appliances and, more specifically, to a new and improved holder and connector for electric cords which is particularly well adapted to be used in connection with electric irons, toasters, or heater plates which are placed on the table, portable lamps, and the like.

It is a matter of common knowledge that electric cords for portable electrical appliances are normally subjected to wear and tear much more than stationary wires, and that a twisting of or the exertion of pressure upon such cords tends to damage the insulation which results in short circuits, personal injuries, repair and replacement costs, and fire hazards. It has also been observed frequently that children, due to curiosity, like to insert nails, pins, wires or other conductive objects into the openings of plug-in sockets, which may result in serious harm.

In order to make electrical appliances safer and to reduce the costs of repairs and replacement, one object of the present invention is the provision of a device of the character described which will prevent the twisting of electric cords and which will automatically wind up that portion of a wire or cord which is not necessary temporarily for a certain use of an electrical appliance, so that no portions of the cord are in the way of the user but are well protected within a housing thus preventing a stepping upon such wire portions or a placing of heavy or hot objects upon them.

Another object of the present invention is the provision of a device of the character described which ordinarily makes it impossible that small children can reach the conductive parts of a plug-in socket when they insert nails or the like into the holes of such sockets in the manner previously referred to.

Still another object of the present invention is the provision of a device of the character described which is light in weight, handy in use, inexpensive to manufacture but of a pleasing appearance and durable as well as adapted to withstand the rough usage to which devices of this type are frequently subjected.

Further objects of the instant invention reside in any novel feature of construction or operation or novel combination of parts present in the embodiment of the invention described and shown in the accompanying drawing whether within or without the scope of the appended claims and irrespective of other specific statements as to the scope of the invention contained herein.

2

In the drawing:

Figure 1 is a side elevational view of the entire device as it appears when it is being used in connection with an electric iron;

5 Figure 2 is a cross-sectional view of a detail on the line 2—2 of Figure 3;

Figure 3 is a vertical sectional view through Figure 2;

Figure 4 is a top plan view of another part of 10 the device; and

Figure 5 is a sectional view on the line 5—5 of Figure 4.

Similar reference characters refer to similar parts throughout the several views.

15 In the drawing the numeral 1 denotes an electric iron which does not form a part of my present invention but which is shown only as an example of an electrical device in connection with which my new and improved cord holder and connector

20 can be used. The contact pins of the iron 1 are rectangular and have horizontal sections 2 and vertical end sections 3. The plug-in-socket 4 has a pair of T-shaped bores each of which consists of a horizontal non-conductive section

25 5 and of a vertical section 6, the latter being provided with a conductive sleeve 7 which fits tightly around the lower portion of a vertical pin section 3. A cover 8 which is hinged at 9 to the socket 4 allows the laying free of portions of the horizontal sections 5, so that the contact pins can

30 be inserted. The cover 8 is normally closed, and the hinge 9 is preferably provided with a spring or with any well known suitable locking device (not shown) which will make it impossible for 35 a young infant to open the cover 8, although an adult can open it without much effort. I also prefer to provide the socket 4 with a screw clamp 10, so that it can be attached to a table board or a shelf or the like whenever that should be convenient. The conductive wires 11 of an insulated electric cord 12 are connected to the sleeves 7 by means of soldering or in any suitable manner.

40 While the construction of the socket 4 just described prevents accidents which may be caused by children, the detail shown in Figures 2 and 3 constitutes a holder and automatic winding device for the wire. This device comprises a housing 15 consisting preferably of four circular sections 16, 17, 18 and 19 of insulating material which are of the same outer diameter and which are connected to one another by means of bolts 20 or in any other suitable manner. Within the housing 15 there are four compartments 21, 22, 23 and 24; and a shaft 25 is rotatably

arranged in the housing 15 and is extended through the compartment 24 and through the center of the compartments 21, 22 and 23. An oblique bore 27 is provided across the shaft 25 in such a manner that its openings register with the compartments 23 and 22 respectively, and the width of the latter is but slightly larger than the outer diameter of the cord 12. In the compartment 21 there is a spiral spring 28 whose one end is attached to the shaft 25 at 29 and whose other end is attached to the section 16 of the housing 15 at 30. In the compartment 24 there is a flat spring 31 whose free end portion rests normally against the shaft 25, engaging a circular row of notches 32, so as to prevent normally a turning of the shaft 25 in an anticlockwise direction. A push pin 33, which has a collar 34 is extended into the housing 15 through the section 19 and is held normally in the position shown in Figure 3 by means of a spring 35. Upon depressing that portion of the pin 33 which protrudes over the outer side of the housing 15 the spring 31 is moved from the position shown in full lines in Figure 3 to the position indicated in dash and dotted lines, so that the spring 31 no longer engages the notches 32, thus allowing the shaft 25 to rotate in either direction.

The cord 12 is slid through an entrance channel 36 into the compartment 23, is passed through the oblique cross bore 27 into the compartment 22, and leaves the latter through an exit channel 37. The spring 28 is set so that it rotates the shaft 25 until one portion of the cord 12 is wound up as a spiral within the compartment 22 while another portion of the cord 12 is wound up as a spiral within the compartment 23, as may be seen in Figures 2 and 3. The cord 12 can then be unwound partially or entirely according to the length required simply by pulling it out of the housing 15, thereby the spring 31 and the notches 32 acting like a pawl and ratchet wheel, so that the cord 12 will be released from the tension which otherwise might be caused by the action of the spring 28. In order to re-wind the cord 12, the pin 33 is depressed whereupon the cord will be rewound and will partially disappear within the housing 15.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having thus fully described my said invention,

what I claim as new and desire to secure by Letters Patent is:

1. An electric cord holder and connector comprising a shaft rotatably arranged within and extended through four adjoining compartments of a housing being provided with an oblique radial bore whose openings register with two of said compartments, resilient means for rotating said shaft being arranged in another compartment, means for stopping the rotation of said shaft being arranged in the fourth compartment, and a wire connected to a plug-in socket being slid through an entrance opening in said housing into one of the two compartments which register with the openings of said oblique bore, said wire passing through said oblique bore and through the other one of said two compartments and leaving said housing through an outlet opening.
2. A device of the character described comprising a housing having a pair of circular compartments whose width is slightly larger than the diameter of an insulated double pole wire and having a longitudinal third compartment as well as a wide circular fourth compartment, a shaft rotatably arranged in said housing and extended through said longitudinal compartment and through the center of said circular compartments and being provided with an oblique cross bore whose openings register with said first mentioned circular compartments, a spiral spring being arranged within said fourth compartment and having one of its ends connected to said shaft while its other end is connected to said housing, a flat spring within said longitudinal compartment being arranged in such a manner that it normally engages a circular row of notches on said shaft, a push pin extending from the outer side of said housing into said longitudinal compartment and resting laterally against said flat spring, and a wire being slid through an entrance opening in said housing into one of the two compartments which register with the openings of said oblique bore, said wire passing through said oblique bore and through the other one of said two compartments and leaving said housing through an outlet opening.

EDMUNDO CORTES.
